SPINAL ADJUSTING DEVICE

Evan W. Stevens, Kendall, Kans.

Application July 5, 1949, Serial No. 103,016

11 Claims. (Cl. 128—69)

1
My invention relates to spinal adjusting devices, and more particularly, to such a device as can be manipulated by the patient himself whereby to provide a means for self-treatment of minor spinal ailments.

As is well known, the several segments or vertebrae forming the spinal column occasionally become misaligned. When this occurs, if it is not promptly remedied, the misaligned segment or vertebrae will tend to become "set" in the misaligned position. However, if treated promptly, the misaligned vertebrae may be readily returned to its proper alignment with the spinal column whereby future ailments resulting from such misaligned vertebrae are avoided. Moreover, prompt treatment heretofore could only be had at the hands of an experienced chiropractor or osteopath, which treatments are relatively expensive and frequently beyond the means of the sufferer.

With the foregoing in view, it is an object of my invention to provide an improved device for self-massaging and adjustment of the spinal column.

A further object is to provide a device such as that last described which comprises a pair of relatively movable frames, a pair of laterally movable spinal adjusting massaging elements carried by one of said frames, and means operative to move the massaging elements laterally towards each other to massage and adjust the spinal column upon movement of the other frame relative to the first mentioned frame.

Other objects and advantages reside in the particular structure of the device, the structure of the several elements forming the same, combinations and sub-combinations of such elements, all of which will be readily apparent to those skilled in the art upon reference to the attached drawings in connection with the following specification, wherein the invention is shown, described and claimed.

In the drawings—

Fig. 1 is a perspective view of one form of the invention;

Fig. 2 is a plan view thereof showing the same applied to a torso, the latter being shown diagrammatically;

Fig. 3 is a rear elevation;

Fig. 4 is a fragmentary vertical sectional view taken substantially on the plane of the line 4—4 of Fig. 2; and

Fig. 5 is a fragmentary horizontal sectional view through one of the massaging elements, parts being shown in plan.

2
Referring specifically to the drawings, wherein an operative concept of the invention has been disclosed and wherein like reference characters have been used throughout the several views to designate like parts, 10 designates generally a relatively movable frame and 20 designates generally a relatively fixed frame.

In the embodiment illustrated, the relatively movable frame 10 comprises a pair of laterally spaced slides 11 which are parallel to each other and have their rear ends connected together by a cross head 12. A relatively heavy striker or hammer 13 is fixed to the cross head 12 intermediate the slides 11. The forward ends 14 of the slides 11 may be connected together by a cross piece 15 which preferably has a pair of laterally spaced hand grips 16 formed thereon or attached thereto in any suitable manner. Obviously, the portion of the cross piece 15 intermediate the hand grips 16 may be eliminated if desired. A pair of compressive springs 17 connect the cross piece 15 to a web 21 of the stationary frame 20 so as to load the movable frame 10 to a rearwardly retracted position relative to the stationary frame 20. As best seen in Fig. 2, the frames 10 and 20 are adapted to encircle a torso 18, the spinal column of which is diagrammatically indicated at 19. Moreover, it should be understood that the frames 10 and 20 are made of lightweight material such as the lighter metallic alloys, and/or plastic, whereby they may be readily supported by the user without making additional support necessary.

The relatively stationary frame 20 in the embodiment illustrated comprises a pair of forwardly extending tubular guides 22 fixedly secured to opposite ends of the web 21 whereby to provide a substantially U-shaped frame. While the guides 22 have been shown as being tubular, it is obvious that any other suitable slidable connection between the guides 22 and the slides 11 may be provided to operatively connect the frames 10 and 20 together.

The web 21 of the stationary frame 20 has formed thereon or attached thereto in any suitable manner a forwardly directed sleeve 23 in which is slidably a cam plunger 24. The back end of the plunger 24 is enlarged to provide a head 25 which is in alignment with the striker 13 as clearly seen in Fig. 2. An expansive spring 26 is interposed between the head 25 and the sleeve 23 whereby to load the plunger to a rearwardly retracted position. The forward end of the cam plunger 24 extends forwardly of the sleeve 23 and preferably is provided with a pair

of laterally outwardly and forwardly diverging cam arms 27.

A pair of massaging arms 28 are pivoted to the web 21 of the movable frame 20 in any suitable manner on opposite sides of the sleeve 23. The forward ends of the arms 28 are vertically enlarged as at 29 and have any suitable massaging pads 30 secured thereto in any suitable manner. In the embodiment illustrated, the arms 28 each comprise a pair of vertically spaced plates connected together by a pair of longitudinally spaced cam followers 31 and 32 which straddle the cam arms 27 of the cam plunger 24. As best seen in Fig. 2, it is obvious that forward movement of the plunger 24 causes the front edges of the cam arms 27 to engage the forward cam followers 31 whereby the arms 28 are swung inwardly towards each other. If, when this occurs, the massaging pads 30 are in engagement with the back of the torso 18 in equally spaced relation to the spinal column 19, it is obvious that the oppositely inward swinging movement of the arms 28 caused by the cam arms 27 will tend to force any laterally misaligned vertebrae back into alignment. Obviously, reverse relative movement of the frames will cause the back edges of the cam arms 27 to engage the cam followers 32 whereby the arms 28 are once more spread apart to the Fig. 2 position. Also, it is preferable that the outer ends of the cam arms 27 be provided with some sort of stops 33 which are adapted to engage the arms 28 to limit lateral outward swinging movement of the latter and maintain the same in operative engagement with the cam arms 27.

In operation, with the parts in the position of Fig. 2, it is obvious that the user's hands are gripping the hand grips 16 and are pressing forwardly with sufficient force to maintain the massaging pads 30 in operative engagement with the back of the torso 18 on opposite sides of the spinal column 19. As aforesaid, the parts are so light that the slight forward pressure, while insufficient to overcome the action of the springs 11, is sufficient to maintain the frames operatively positioned against the back of the torso 18. If the user will now press forwardly with relatively great force on the hand grips 16, the movable frame 19 will be moved forwardly relative to the stationary frame 20 whereby the striker or hammer 13 engages the head 25 of the cam plunger 24 and forces the cam plunger forwardly. At the same time, a slight forward movement will be imparted to the frame 20 by virtue of the relatively great inertia of the weight or striker 13. Thus, as the arms 28 are swung inwardly toward each other with a massaging action, they are also pressed forwardly with the frame 20. Thus, the massaging action is a forward and lateral inward movement tending to press the vertebrae forwardly at the same time aligning them. Such alignment is accomplished by the vertical elongations 29 of the massaging arms 28 which tend to make the misaligned segments or vertebrae self-aligning with respect to those vertebrae already aligned.

While I have shown and described what is now thought to be a preferred embodiment of the invention, it is to be understood that the same is susceptible of other forms and expressions. Consequently, I do not limit myself to the precise structure shown and described hereinabove except as hereinafter claimed.

I claim:

1. A spinal massaging device, comprising a U-shaped frame including a pair of parallel tubular guides open at both ends and a web rigidly

connecting said guides together in the region of the rear ends thereof, a pair of slides, there being a slide slidable in each guide, each slide having a front and a rear end extending respectively forwardly and rearwardly of its guide, said front ends of said slides providing hand grips, tension springs connecting said hand grips and said web together so as to load said slides to rearward retracted positions, a tubular sleeve fixed to said web between said guides in parallel relation thereto, a plunger slidable in said sleeve, said plunger having a back end extending rearwardly of said sleeve and formed to provide a head, a plunger spring interposed between said head and sleeve and loading said plunger rearwardly to a retracted position, said plunger having a front end formed to provide a pair of forwardly and laterally directed cam arms, a pair of forwardly extending massaging arms pivoted to said web, there being a massaging arm on each side of said sleeve, said massaging arms having front ends, massaging pads on said front ends of said massaging arms, said massaging arms each having a pair of spaced anti-friction cam followers straddling a cam arm whereby to swing said massaging arms laterally inwardly upon forward movement of said plunger, a cross head connecting said rear ends of said slides together rearwardly of the web, a striker fixed to said cross head between said slides, and said striker being located to impact said plunger and move the same and said frame forwardly upon forward movement of said slides and cross head relative to said guides and web.

2. A spinal massaging device, comprising a U-shaped frame including a pair of parallel guides and a web rigidly connecting said guides together in the region of the rear ends thereof, a pair of slides carried by said respective guides for sliding movement longitudinally thereof, a cross head connecting said slides together rearwardly of said web, spring means engaging said frame and operatively connected to said slides so as to load the latter to a rearwardly retracted position, a tubular sleeve fixed to said web between said guides in parallel relation thereto, a plunger slidable in said sleeve, said plunger having a back end extending rearwardly of said sleeve and formed to provide a head, a plunger spring interposed between said head and sleeve and loading said plunger rearwardly to a retracted position, said plunger having a front end formed to provide a pair of forwardly and laterally directed cam arms, a pair of forwardly extending massaging arms pivoted to said web, there being a massaging arm on each side of said sleeve, said massaging arms having front ends, massaging pads on said front ends of said massaging arms, said massaging arms each having a pair of spaced anti-friction cam followers straddling a cam arm whereby to swing said massaging arms laterally inwardly upon forward movement of said plunger, a striker fixed to said cross head between said slides, and said striker being located to impact said plunger and move the same and said frame forwardly upon forward movement of said slides and cross head relative to said guides and web.

3. A spinal massaging device, comprising a U-shaped frame including a pair of parallel guides and a web rigidly connecting said guides together in the region of the rear ends thereof, a pair of slides carried by said respective guides for sliding movement longitudinally thereof, a cross head connecting said slides together rearwardly of said web, spring means engaging said frame and oper-

atively connected to said slides so as to load the latter to a rearwardly retracted position, a pair of forwardly extending massaging arms pivoted to said web in laterally spaced relation, a cam, means mounting said cam on said web between said arms for forward and rearward sliding movement, spring means loading said cam to a rearwardly retracted position, cam followers operatively coupling said cam to said arms whereby to swing the latter inwardly upon forward movement of said cam, striker means fixed to said cross head in alignment with said cam so as to strike the latter and move the same and said frame forwardly upon forward movement of said slides relative to said frame, and means operatively connected to said slides whereby they may be actuated forwardly relative to said frame.

4. A spinal massaging device, comprising a U-shaped frame including a pair of parallel guides and a web rigidly connecting said guides together in the region of the rear ends thereof, a pair of slides carried by said respective guides for sliding movement longitudinally thereof, a cross head connecting said slides together rearwardly of said web, spring means engaging said frame and operatively connected to said slides so as to load the latter to a rearwardly retracted position, a pair of forwardly extending massaging arms pivoted to said web in laterally spaced relation, constantly interengaging means in part carried by said cross head and in part by said respective arms and operable to swing said arms laterally in opposite directions upon forward movement of said slides relative to said frame, and hand-grip incorporating means for actuating said slides.

5. A spinal massaging device comprising a pair of torso receiving frames, said frames comprising laterally spaced slidably interengaging guide portions at each side, cross members connecting the respective guide portions of said frames adjacent the rear ends of the latter, a pair of laterally spaced spinal massaging arms pivoted to the cross member of one of said frames between its guide portions and for swinging movement in a plane parallel therewith, arm operating means operatively connected to said massaging arms and carried by said last mentioned frame, actuating means for said arm operating means and carried by the cross member of said other frame, and said actuating means and operating means positioned to interengage upon relative movement of said frames in one direction.

6. The combination set forth in claim 5 and said arm operating means comprising a plunger slidably carried by the cross member of the arm-carrying frame, and arm control means operatively connected to said plunger and said arms.

7. The combination set forth in claim 5 and said arm operating means comprising a plunger slidably carried by the cross member of the arm-carrying frame, arm control means operatively

connected to said plunger and said arms, and said actuating means comprising a striker carried by the cross member of said second mentioned frame.

8. The combination set forth in claim 5 and said arm operating means comprising a plunger slidably carried by the cross member of the arm-carrying frame, arm control means operatively connected to said plunger and said arms, said actuating means comprising a striker carried by the cross member of said second mentioned frame, and yielding means normally urging the second mentioned frame rearwardly to maintain said striker out of engagement with said plunger.

9. The combination set forth in claim 5, and hand grip-including actuating means for said second mentioned frame and carried by its guide portions adjacent the ends thereof remote from its cross member.

10. The combination set forth in claim 5, and said arm operating means comprising a plunger slidably carried by the cross member of the arm-carrying frame, arm control means operatively connected to said plunger and said arms, said actuating means comprising a striker carried by the cross member of said second mentioned frame, and hand grip-including actuating means for said second mentioned frame and carried by its guide portions adjacent the ends thereof remote from its cross member.

11. The combination set forth in claim 5, and said arm operating means comprising a plunger slidably carried by the cross member of the arm-carrying frame, arm control means operatively connected to said plunger and said arms, said actuating means comprising a striker carried by the cross member of said second mentioned frame, yielding means normally urging the second mentioned frame rearwardly to maintain said striker out of engagement with said plunger, and hand grip including actuating means for said second mentioned frame and carried by its guide portions adjacent the ends thereof remote from its cross member.
